UNITED STATES PATENT OFFICE.

RICHARD C. ALTON, OF PHILADELPHIA, PA., ASSIGNOR TO F. ODEN HORSTMANN, SAMUEL CLARKSON, AND WILLIAM P. ELLISON, OF SAME PLACE, TRUSTEES OF THE ESTATE OF WILLIAM J. HORSTMANN, DECEASED.

IMPROVEMENT IN MACHINES FOR COVERING STRANDS FOR GIMP.

Specification forming part of Letters Patent No. 146,222, dated January 6, 1874; application filed November 24, 1873.

To all whom it may concern:

Be it known that I, RICHARD C. ALTON, of the city and county of Philadelphia, State of Pennsylvania, have invented an Improvement in Machines for Covering Strands, of which the following is a specification:

My invention relates to machinery for manufacturing the silk - covered gimp - twisted strands which constitute the gimp-bullion used in making tassels, fringes, &c.; and the object of my invention is to manufacture gimp of superior quality, and with less silk than heretofore, by causing the core *a* of cotton to pass along a groove, *b*, in a plate, *B*, to the flier, while the silk strands *d* are caused by a guide-rod, *e*, to be forced against and spread over the said plate before they reach the core around which they are wound, all as shown in the front view, Figure 1, and sectional plan, Fig. 2, of the accompanying drawing.

A represents a portion of the frame of the machine, which, with the exception of the devices mentioned above, is similar to other machines for winding silk around cores of cotton. To this bar *A* is secured the guide *A'* and plate *B*, the former having an eye, through which passes the cotton core *a*, and which serves to direct the latter to the groove *b* in the plate *B*, along which the core passes to the usual flier common to machines of this class. The strands *d* of silk pass from bobbins around an inclined rod, *h*, secured to the frame *A*, and thence behind a rod, *e*, attached to the plate *B*, and thence, across the portion *f* of the said plate, to the core, as the latter is twisted by the flier, and traverses downward through the groove.

On reference to the sectional plan, Fig. 2, it will be observed that the guide-rod *e* is so situated that the silk strands must be pressed against the plate *B* in their passage from the said rod to the core in the groove. This pressure necessarily spreads the strands against the plate and presents the strands to the core in a flattened condition, which insures the more effectual covering of the said core than when they are directed to the latter in a close mass; in other words, comparatively few strands of silk, when thus spread and flattened, will more effectually cover the core than a greater number of strands directed to the core in the usual manner.

Any tendency of the tension on the silken strands to displace the core will be resisted by the groove in the plate, which maintains the core and the gimp resulting from the winding of the silk around the core in a straight course. I prefer to secure the guide-rod *e*, at one end, to the plate *B* by means of a set-screw, *i*, so that it can be adjusted to impart more or less tension to the silken strands.

I claim as my invention—

The combination, in a machine for covering strands, of the grooved plate *B* with the guide-rod *e*, for the purpose specified.

In testimony whereof I have signed my name to this specification in the presence of two subscribing witnesses.

RICHARD C. ALTON.
